UNITED STATES PATENT OFFICE.

PATRICK SHEEDY, OF LOS ANGELES, CALIFORNIA.

DRIFTING DEVICE FOR LOCOMOTIVES.

1,022,052.

Specification of Letters Patent.

Patented Apr. 2, 1912.

Application filed June 27, 1911. Serial No. 635,664.

To all whom it may concern:

Be it known that I, PATRICK SHEEDY, a citizen of the United States, and a resident of Los Angeles, county of Los Angeles, State 5 of California, have invented certain new and useful Improvements in Drifting Devices for Locomotives, of which the following is a specification.

The object of my invention is to improve 10 the structural form of the circulator for locomotive cylinders for which patent was issued under Number 704,130 issued July 8, 1902, to Patrick Sheedy and Alexander Campbell. In this invention the same results are accomplished as set forth in that 15 patent, but by the new method of construction several very important advantages are gained, not only so far as the cheapness and ease of attachment are concerned, but also in 20 the resultant use of the invention. These advantages may be partially summarized as follows:

First, this invention provides a protective conduit for conducting the air and gases of 25 suitable temperature in circulation, from one end of the cylinder to the other. Thus the temperature of the air and gas conveyed back and forth in this manner is not lowered to such an extent as in the form shown 30 in the patent where the conducting pipe is exposed to the atmosphere.

Second, by casting the conduit with the cylinder body the mechanism can be applied much more cheaply, as the valve can be 35 attached directly to the duct at the ends of the cylinder thus requiring no extra piping.

Third, there being no external pipe the conduit means is not exposed, and thus not liable to damage by external means.

Fourth, the clearance space, which is very 40 important is reduced by the improved structure to a minimum, which means economy in operating results.

These and other advantages will be explained hereinafter fully in detail.

In the accompanying drawing Figure 1 is 45 an end view of a locomotive cylinder, partly in section, showing the application of my improved circulator for locomotive cylinders. Fig. 2 is a side view partly in section, and Fig. 3 is a vertical longitudinal section of the valve for controlling the circulating system.

In utilizing my invention it is applicable 50 to any type of locomotive engine, equipped with any type of valves for controlling the

supply of steam to the cylinder. Thus in the drawing 4 represents the cylinder, having therein the usual piston, (not shown), and 5 the steam chest. Between the cylinder and the steam chest, on one side, is a horizontal rib 6, cast with the main body of the cylinder and chest, which has a cored conduit 7, extending from end to end, so that the jacket 8 of the engine cylinder and 60 chest surrounds and covers up this rib or cored body. At each end of this conduit 7, is a port 9, communicating with the cylinder, and each end of the conduit has attached thereto a controlling valve shell 10, which 65 has a flange 11, by means of which it may be secured to the end of the cored rib. The body of the valve which projects out from the flange has within it a tubular piston 12, to carry the rod 13 of a valve 14. This 70 valve is seated against the end of the conduit 7, and the location of the valve is such that the normal working pressure of the live steam or exhaust of the cylinder will close or seat the valve.

The inner end of the valve shell has a closure cap 15 through which the piston 13 passes, and a coiled spring 16 is interposed between the closure cap 15, and outer end of the piston 12, so that if no pressure 80 should be exerted inwardly against the piston 12, the action of the spring would be to unseat the valve 14. As, however, a steam pipe 17, leads from the steam chest to the outer end of the valve shell, it is obvious that 85 when live steam is admitted to the steam chest its pressure against the piston 12 will be sufficient to seat the valve 14, but when steam does not enter the steam chest and the locomotive is running free the valve 14 90 is unseated by the action of the spring, so that there is a direct free passage from one end of the cylinder to the other, which constitutes a by-pass integral with the cylinder 95 casting.

The outer end of the valve shell 10 has a drain-cock 18, and the pipe 17 from the steam chest has a valve 19, so that steam may be entirely cut off from the circulating valve 10.

It is obvious that the structure herein set forth greatly simplifies and cheapens the application of a circulating system, and dispenses not only with the exposed pipe but also greatly reduces the clearance space, as 110 the valve is by this means located within the jacket of the cylinder, and not on the outer

end of a projecting pipe as shown in the former patent alluded to, and I do not, therefore, add the volume of the space in the pipe between the end of the cylinder and valve to the clearance at the end of the cylinder.

The conduit connecting one end of the cylinder with the other destroys the vacuum at each end of the cylinder as the piston leaves it. In the absence of this air circulating conduit, the receding piston creates a vacuum at the end of the cylinder from which it is receding at a time when the main valve covers the ports. The vacuum which is the result of this piston movement, in the absence of the circulating conduit, would be supplied from the smoke arch through the exhaust pipe and cavity. The result is the introduction of hot smoke, gas and cinders as well as increased consumption of fuel, due to the draft produced on the fire to supply this vacuum.

What I claim as new is:—

1. A locomotive cylinder having a circulating conduit cast with the cylinder, and having a cored port communicating directly between the end of said circulating conduit and the cylinder.
2. A locomotive cylinder having a circulating conduit cast with the cylinder and a cored port communicating directly between the end of said circulating conduit and cylinder, and a controlling valve attached at each end directly to the conduit.
3. An engine cylinder having a by-pass from one end of the cylinder to the other

end, said by-pass being integral with the cylinder casting, and a valve at each end of the by-pass, so located and arranged that when the engine is running free the steam or air within the cylinder will exhaust from one end of the cylinder to the other through said by-pass.

4. An engine cylinder having a by-pass from one end of the cylinder to the other end, integral with the cylinder casting, a valve at each end of the by-pass so arranged that when the engine is running free the steam or air within the cylinder will exhaust back and forth from end to end through the by-pass, and a high pressure steam connection leading to and adapted to normally seat each valve in the by-pass.

5. The combination with a locomotive cylinder, of a circulating conduit cored through the cylinder body, and provided with a port at each end of the cylinder communicating with the circulating conduit, a valve at each end connected directly with and seated against the ends of the conduits, the valve stem having a piston with a retractile spring to unseat the valve, and a pipe connection with the steam chest of the cylinder to normally seat said controlling valve.

Signed in the city and county of Los Angeles, State of California, this 26th day of May, 1911, in the presence of witnesses.

PATRICK SHEEDY.
